US0D1071757S

(12) **United States Design Patent** (10) **Patent No.:** **US D1,071,757 S**
(45) **Date of Patent:** **** Apr. 22, 2025**

(54) **GLOBAL POSITIONING DEVICE**

(71) Applicant: **Tenways Technovation Europe B.V.**,
Amsterdam (NL)

(72) Inventor: **He Huang**, Amsterdam (NL)

(**) Term: **15 Years**

(21) Appl. No.: **35/519,578**

(22) Filed: **Dec. 15, 2023**

(80) **Hague Agreement Data**

Int. Filing Date: **Dec. 15, 2023**

Int. Reg. No.: **DM/234085**

Int. Reg. Date: **Dec. 15, 2023**

Int. Reg. Pub. Date: **Dec. 29, 2023**

(51) **LOC (15) Cl.** **10-04**

(52) **U.S. Cl.**

USPC **D10/70; D10/78**

CLAIM

The ornamental design for a global positioning device as shown and described.

DESCRIPTION

2. Global positioning device

2.1 : Perspective

2.2 : Perspective

2.3 : Top

2.4 : Left

2.5 : Front

2.6 : Back

The present design represents a global positioning device, to be embedded in a frame of a bicycle and for emitting GPS sensor data about the position of the bicycle. The broken
